UNITED STATES PATENT OFFICE

CHARLES P. MADSEN, OF NEW YORK, N. Y., ASSIGNOR, BY MESNE ASSIGNMENTS, TO
WILLIAM W. VARNEY, OF BALTIMORE, MARYLAND

PHONOGRAPH

Application filed May 1, 1925. Serial No. 27,206.

The object of my invention is the construction of an improved portable phonograph.

A further object of my invention is a new process of transmitting vibrations.

A further object of my invention is the providing in a phonograph an improved reproducing means.

A further object of my invention is the providing in a phonograph an improved support for the reproducing means.

A further object of my invention is the providing in a phonograph means for folding the support for the reproducing mechanism.

With the foregoing and other objects in view, my invention consists of the methods employed, combination and arrangement of systems, apparatus and means as hereinafter specifically provided and illustrated in the accompanying drawings wherein is shown the preferred embodiment of my invention, but it is understood that changes, variations and modifications may be resorted to which come within the scope of the claims hereunto appended.

While several of the novel means embodied in this application may be used in other structures, and in consequence thereof, form the subject matter of other applications, the coordination of the same in an organized machine of the character described is new and as such, are claimed herein in such organization, as will hereinafter appear.

I would refer to the co-pending applications and patent as follows: Wave reproducing device and process concerning the same, filed August 5th, 1924, Serial No. 730,152; Method and means of transmitting power, filed February 2nd, 1925, Serial No. 6,414; Method of supporting phonograph reproducing system, filed February 2nd, 1925, Serial No. 6,415; issued Sept. 24th, 1929, Patent No. 1,729,224.

In the drawings of the herein described embodiment of my invention, Figure 1 shows my improved phonograph in perspective, open, assembled, and in playing condition, the record in place on the turntable, and a spare vibrating member stored in the cover;

Fig. 2 is a plan view of the phonograph without the case or cover in condition for playing, a record being shown on the turntable, partially broken away; Fig. 3 is a side view in elevation of the phonograph as removed from the case and cover, and is shown in connection with the arrows 3-3 indicated in Fig. 2; Fig. 4 shows a fragmentary detail in elevation of the reproducer supporting arm in its lowered, limited position, its swing being governed by limit stops provided for the purpose; Fig. 5 is an enlarged vertical section of the supporting arm swivel mounting taken on line 5-5 of Fig. 3; Fig. 6 shows the pin which is used in the swivel mounting as shown in Fig. 5, but in its bowed condition before entering whereby a spring-tight fit is secured to prevent backlash or vibration, thus insuring quiet action; Fig. 7 is a view of the subject matter shown in Fig. 4, but taken at right angles to Fig. 4, as shown by the arrows 7-7, and shows particularly the limit of action in its plane of movement, said movement being substantially at right angles to that shown in Fig. 4; Fig. 8 is an enlarged detail cross-sectional view of the reproducer head; Fig. 9 is an enlarged fragmentary sectional view in detail of the reproducer head or mechanism taken on line 9-9, of Fig. 2; Fig. 10 is an enlarged sectional view of the vibrating member securing means showing in elevation a part of the needle carrying mechanism taken through line 10-10 of Fig. 9; Fig. 11 is a cross-sectional view taken through line 11-11 of Fig. 9, and shows particularly the means for securing together the reproducer head; Fig. 12 is a detail view of the reproducer operating member which is being wound with the rubber band under high tension; and Fig. 13 shows the reproducer operating member in a modified surrounding medium as the same is being stretched or positioned thereon and consists of a vulcanized caoutchouc tube 56 of rather small size compared to the reproducer operating member, so that when the same is pulled thereon it is stretched or in high tensioned condition.

Similar numerals refer to similar parts throughout the several views.

1 is the case. 2 is the cover of the case which is operably hinged to the case 1. 5 are the retaining springs or members in the cover, under which are carried or secured the blanked vibrating member 4.

5 is the securing pin for securing the vibrating member together and operates in raised and depressed portions 6 and 7. Blanked vibrating member 4 is provided centrally with an opening 8 through which its securing means operates and preferably is formed so as to avoid double thickness 15 of the vibrating member blank under the securing means. In the construction shown the pin in its functioned position is an element of a cone, the pin being preferably pointed at one end and formed into a handle 20 at the other. The vibrating member 4 may be of any suitable material. For this purpose I have found that any light rigid material will work; e. g. vulcanite, vulcanized fibre and celluloid. I have found that the 25 best results are produced by impregnating a grade of paper known as 70 lb. jute with rosin cut in bezol to stiffen the paper and then waterproof same by coating with a thin varnish.

20 Referring particularly to Fig. 10, 9 is a cone member secured to rocker arm 10 by means of stud pin 11 and provided with a shoulder and lock nut 12. I have found that the successful operation of my phonograph depends in a large degree upon the mass of the vibrating parts or elements, which are vibrated by the record. In the construction of the actual machine I have discovered that an alloy of aluminum known 40 as Duraluminum gives very satisfactory results. 13 is a conjugate cone member fitting within cone 9, and between these two cone members 9 and 13, is secured the formed up blanked vibrating member 4. The blanked 45 vibrating member 4 is secured together by pin 5, in raised and depressed portions 6 and 7 forming a truncated cone of a certain angle as shown about 31° from base line, the angle of cone 9 is less, say 30°, and the 50 angle of cone 13 is still less, say 29° from base line, in order that upon clamping said cones 9 and 13 on the truncated vibrating member 4 a tightening effect on the edge of cones 9 and 13 is produced to avoid vibration 55 at this point and it also tends to rigidify vibrating member 4. Upon tightening up cones 9 and 13, the two cones become parallel or of the same angle, thus giving a rigid structure. 14 is a knurled securing 60 nut for operating upon stud pin 11 to secure the said two cones, 9 and 13, together, and is operably secured to cone 13 for convenience in handling said cone 13, in a swivel manner. The thread on stud pin 11 upon 65 which knurled nut 14 operates is of a very

coarse pitch for convenience. I do not limit myself to the above construction or angles.

On cover 2 is provided a spring fastener 15, provided with an engaging tongue 16 to engage the member to which it is secured 70 in order to prevent side motion of same so that it will always register with the other member it is to fasten. On spring fastener 15 is catch 17, which engages with the conjugate member or opening in the part to 75 be secured.

91 is a rubber suction foot, (see Fig. 5) within which is holding washer 92. 93 is the leg or spacer secured to the top plate 18, shown in Fig. 2, supporting it on case 1, and has 80 secured to it holding washer 92 by screw 94.

95 is the handle for carrying the case shown in Figs. 1, 2, and 3, and is supported by shouleder screw 96, which screw threads into top plate 18 through a hole in case 1 and secures 85 flange 20 of the top plate 18 to case 1.

Referring to Fig. 10, 18 is the top plate of the phonograph proper. I have found that a very satisfactory result is obtained by stamping the top plate out of sheet metal. 90 This enables me to provide therein various raised portions, stops, etc. 19 is an annular bead. This stiffens the top plate and further has a tendency to prevent any possible vibration of same or warping which might occur 95 from the various strains exerted upon said top plate.

In the central portion of top plate 18 is raised portion 21 in which is secured bearing 22, in which operates turn-table spindle 23. 100 Near one corner of the top plate 18 is a formed-up portion 24 forming a bearing for the winding shaft 25. 26 and 27 are lanced projections forming stops to limit the movement of supporting means 28. 31 are marks in the top plate 18 indicating the correct position of control handle 105. Cover 30 is provided with raised projection 32, which, when the cover is in closed position, acts as a support for stored records, keeping the same 105 free from the turn-table, in connection with the other projections described later. This is especially shown in Fig. 2, said cover being pivotally mounted on top plate 18. 33, 34 and 35 are needle receptacles, 36 is a receptacle in which the reproducer head fits when in closed position, thus protecting the needle and operating parts.

Supporting means 28 is fulcrumed to top plate 18 by bolt 37 provided with lock nuts 120 38 and compression spring washer 39. On supporting arm 28 is projection 40 forming one of the supports for the records stored over the turn-table, keeping the same clear of said turn-table when said supporting means 28 is in housed or closed position; cover 42 which covers needle receptacles 34 and 35 when said arm is housed is secured to said supporting means by lanced projections from said cover 125 embracing said supporting means.

Referring now to Figs. 8, 9 and 10, 43 is the pin as shown in Fig. 11 bowed before insertion. 44 is the sleeve which is secured to the supporting means 28 by riveting or other desirable methods. 45 is the yoke journalled on pin 43 upon which pin operates sleeve 44. In yoke 45 is fulcrumed supporting arm 41 by means of shoulder pin 46 secured to the same by riveting or other desirable means 10 after having assembled thereon supporting arm 41. On the head of shoulder pin 46 is secured counter-balance spring 47, which spring tends to support reproducer supporting arm 41. The purpose of this counter-balance spring 47 is to prevent the effect of gravity on the reproducer head 48 and its conjugate 49 from exerting too high a pressure on the needle point on the record. The amount of mass necessary for producing the 20 proper inertia for reproduction is greater than that which the record grooves will stand when the entire weight rests in the grooves. By providing a means by spring 47 for counter-balancing a part of this weight, the full 25 effect of the mass is utilized in reproducing but the pressure on the record is diminished. It has heretofore been customary to limit the weight of sound boxes or reproducers to between 5 and 6 ounces. I obtain better results 30 by making this mass from 7 to 8 ounces and with the counter-balance spring 47 balanced out a little over half of it, thus making the needle pressure between 2 and 3 ounces. The effect of this counter-balance spring is not 35 only to reduce the surface noise and the wear of the record but also to reduce the load on the motor, thereby making it possible to play large records with less motive power than heretofore, and also making the playing more 40 regular.

Reproducer head 48 is detachably secured to reproducer supporting arm 41 by means of pilot pin 57 and knurled screw 58. The reproducer illustrated in Figs. 9, 10, 11 and 45 12 is the embodiment of a new method of generating air waves of sound frequency when operated either mechanically or electro-mechanically. It possesses many advantages over the means of generating air waves of 50 sound frequency heretofore used. The distortion inherent to the old type of diaphragms as well as that inherent to horns is practically eliminated.

It is also possible to so adjust it that the 55 system does not generate vibrations other than those imparted by the actuating means and thus the timbre and the pitch of the original are more perfectly reproduced.

Referring to Fig. 8, 113 is a handle attached to the reproducer head for the convenience of lifting the same.

48 is the reproducer head and weight, 49 being its conjugate member, said two members being secured together by screws 50 or 65 other suitable means. 51 is the reproducer

spindle. This spindle is a part of the rocker arm 10, which may be either integrally or otherwise secured, and in the same structure there is also formed a needle-carrying appliance for needle 55, consisting of socket 70 52 having broached corners 53 and 54. 56 is a flexible band. I have found vulcanized caoutchouc very desirable for this purpose. It is wound on reproducer spindle 51 while being stretched to almost breaking point, and 75 a sufficient amount is wound on to slightly more than fill the hole formed between the reproducer head and weight 48 and the conjugate member 49, then said reproducer head 48 and conjugate member 49 are clamped together so as to compress the substance around spindle 51 while being in its attenuated state. This compression adjusts the reproducer for correct response. This also forms a sound 80 insulation.

Referring to Figs. 9, 10, and 11, (the reproducing system). It will be understood by those skilled in the art that the performance of this part of the phonograph is influenced very much by the proportions of the parts. The drawings are made practically to scale, showing relative sizes, and a fairly good idea of the proportions will be obtained by knowing that screw 54 is a standard screw used in present sound boxes and the hole 52 is broached to take a standard needle to the correct depth. There must however exist a rather more accurate proportion between the sizes of spindle 51 and the resilient material 56 and the size of the two grooves in reproducer head 48 and its conjugate member 49, which constitutes the cylindrical cavity in which spindle 51 with its resilient layer coating is compacted by screw 50. If the amount of surface is too small the material 105 will be short lived; if the amount of surface is too great it will cause too great a resistance of the needle point and record wear is the result. If the thickness of the layer is too great the reproduction will be lacking in 110 brilliancy. If too thin a layer of the material is used it will also tend to produce a high resistance of the needle point, but in addition it will be short lived because irregularities in the contacting surfaces will cause cutting or injuring of the material at local points. I have found for instance in the case of using for the resilient member a tightly wound rubber band that the correct size for the spindle 51 is .146" in diameter 115 by 1" long, and the thickness of the rubber band when wound should be .018 and in this case the diameter of the hole in which this spindle goes is made with a #18 (.169") drill, when these two parts are clamped together with a .02 liner which is removed after drilling.

I have found that the best results both as to volume and clearness are obtained by using vulcanized caoutchouc in a highly stretched 120 125 130

condition and then compacted as a resilient member, and that very good results can be obtained with almost any light organic material. I have found, for instance, layers of 5 linoxon adaptable for this use, although not quite equal to that produced by vulcanized caoutchouc. By linoxon I mean a layer of nearly completely oxidized linseed oil.

59 is the turn-table which is secured to 10 turn-table spindle 23 by screws or other suitable means 60. On the edge of the turn-table 59 is formed a flange 61, the inner periphery of which flange operates as a driving means for the governing mechanism as described 15 later. The turn-table is covered with felt or other suitable material, the central portion being omitted to have access to the screws 60. The center of the turn-table is depressed at 62 for stiffening.

20 Turn-table spindle 23 goes through bearing 22, which bearing is secured to top plate 18, as heretofore described, and has secured to it set collar 63 to prevent said spindle from becoming displaced upon inversion of the 25 machine, and also has secured to it or formed integral therewith pinion 64, which pinion drives the same, and is driven by gear 65 which gear is secured to or formed integral with spring housing 66, to which housing is 30 secured the outer end of main spring 67 by means of a bracket 68 secured to the housing 66 and providing a means of carrying a headed stud pin 69 over which the main spring 67 is placed and slid into position. 35 70 is a bracing member which also slips over and is positioned on said pin 69. Bracing member 70 when in position, tends to cause the main spring in its unwinding to reel off from its outer layers with comparatively a 40 small amount of sliding of the adjacent convolutions. The other or inner end of main spring 67 is secured to securing sleeve 71 by hooking upon the same. Securing sleeve 71 operates on motor stud 72 and is secured to 45 winding gear 73 by projections 74. I have found that riveting is a quick and convenient method. Stud 72 is provided with an ex- 50 panded collar 114 so located that it provides a lower or down-thrust bearing for winding gear 73 and also provides an upper-thrust bearing for hub 115 which is secured onto motor gear 65 by any suitable means.

55 75 is a pinion which drives a gear 73 and is operated by winding shaft 25, to which it is secured by any suitable means.

Winding shaft 25 is journalled in top plate 18 and has secured on its upper end winding bracket 77, which bracket is shown in 60 Fig. 2. 78 is the winding crank provided with handle 79, and engaging supporting pin 80, which pin forms the double function of supporting the crank while winding, and also 65 engaging the winding bracket in recess 81, thus increasing the rigidity of the winding

crank, the said winding crank 78 being fulcrumed to winding bracket 77 at 82 in an offset position to permit the playing of 12" records. The fulcrumed end of winding crank 78 is extended beyond the fulcrum 70 within the jaws of the bracket to provide a stiffening means.

Referring to Fig. 3, a washer 16 of suitable material, preferably brass, is provided on winding shaft 25 between winding pinion 75 75 and the top plate 18.

76 is the winding check spring and operates on winding shaft 25 to prevent the same from unwinding, not being secured thereon other than by its own tension, and the other end of such spring being fastened to flange 80 20 of the top plate 18, as shown in Fig. 3. Winding crank 78 when in closed or inoperative position is of such a height and in such a position to support in conjunction with the other record supporting means the records which may be stored over the turn-table parallel therewith but not touching the same, which is clearly shown in Fig. 3. In top plate 18 is cup 83 in which handle 79 fits 85 when in an inoperative or stored position, thus insuring the proper location for the same to support the said records and being within the limit of the box when the cover is placed thereon.

90 I have found that in light phonographs a considerable difficulty is experienced in winding up the driving spring owing to the lightness of the machine and its slipping over a surface upon which it may be placed. To overcome this I have devised suction feet, upon which the phonograph or its case rests. These suction feet when on smooth surfaces 95 form an air suction and hold so that the phonograph may be wound without touching the same except by the handle.

100 84 is the bottom plate which is secured to top plate 18 by pillars and securing means 85 and by motor stud 72, thus forming a rigid structure for the support of the motor stud and of the lower bearing 86 of the turn-table spindle 23.

105 Spring housing 66 is formed by lancing gear 65, which method I have found very satisfactory. The lower end of turn-table spindle 23 operates in bearing 86 and is supported on ball 87 in the bottom of said bearing 86. Said bearing 86 is secured to bottom plate 84. 88 is a fibre washer between the top plate 18 and the winding gear 73 and is provided with an oiling hole 89. 90 110 is a paper washer between spring 67 and the driving gear 65 to keep dirt out and to keep grease in.

115 I have discovered an entirely new system of driving, or transmitting power, which I call the "air suction drive".

120 The manner of operation of my new air suction drive not illustrated in which the

rim of the turn-table is represented and 98 represents the wheel, while 101 is the holding means for this wheel. It will be seen that this wheel is so positioned with relation to the rim 61 that it is under a slight compression.

5 I preferably make this wheel of any soft organic material either adapted to having formed or already possessing a large number 10 of cup-like cavities in its rim. I preferably use vulcanized caoutchouc in which case I form the cups by moulding.

I have also found that a wheel cut from sheets of sponge rubber having a thin solid 15 wall on each side is satisfactory. This wheel, when mounted as described develops small amount of frictional contact but by far the larger part of the torque is developed by the suction of cup-like cavities.

20 It will be seen that as the cup approaches the rim member 61 it is compressed and part of the air forced out, which causes a partial vacuum and a clinging of the wheel.

The vacuum cups furthermore hold so 25 tenaciously to their co-acting surface that if the governor be suddenly stopped it stops the turn-table almost instantly with practically no slippage.

The governor and its driving means not 30 shown gain several advantages by driving the governor from the edge of the turn-table; it increases the regularity and quietness of any spring motor so greatly that I am enabled thereby to eliminate the usual jackshaft 35 or worms and drive by a single reduction from the spring barrel to the turn-table shaft. This fact also enables me to eliminate intermediate gearing between the winding gear and spring barrel. I thus produce a 40 very simple, very quiet, and highly efficient motor.

The best results are obtained, however, by using my new air suction or vacuum cup drive set forth more particularly in my co-pending application filed February 2nd, 1925, Serial Number 6,414.

I have discovered, that by making a driving wheel of soft, preferably organic material either already having in its surface 45 or being adapted to having formed in its surface a large number of small cup-like cavities, a new result is obtained. The increase in mechanical efficiency without slippage by this means of transmitting power 50 is so great that I am enabled by its use to drive the governor much faster than formerly from the edge of the turn-table, smaller than standard, and at the same time require less motive power than motors heretofore used. It is furthermore absolutely silent.

I prefer to make this wheel by moulding a ring of vulcanized caoutchouc forming the cup-like cavities in its outer rim. I preferably mount this ring in two members so 55 shaped that when compressed toward each

other they will cause the ring to expand. This construction is shown in Fig. 2 in which 98 is the formed rubber ring, provided with compression washers and adjusting screw.

Fig. 37 is a plan view of this vacuum cup drive 70 in action with a part of the top washer 99 removed showing the relation of the vacuum cups to its co-acting rim 61 of the turn-table. It will be seen that as the wheel revolves the cups are slightly compressed producing a partial vacuum in those which are leaving the rim, causing them to clean their tube. The amount of power consumed to produce this effect is many times less than that necessary to obtain the same degree of traction with a friction drive.

I may also make this wheel by punching 75 discs out of a grade of sheet rubber known to the rubber stamp trade as cushion. This is a sponge rubber with thin outside solid walls and a disc cut from it has cup-like cavities in its edge similar to those illustrated.

Referring now to the governor construction shown in Fig. 2, 102 is the governor casting on the inner periphery of which is chased or formed a coarse pitch thread 103, preferably of at least 4 leads, to enable quick action of a speed control disc 104. The speed controlling disc is threaded to fit thread 103, disc 104 being operated by control handle and pointer 105, which is secured to said disc by an adjusting means. The disc 104 has a slot 90 106 whereby to permit adjustment of the disc with regard to the pointer so that the same may correspond with the speed marking on the top plate. Said disc is also provided with an opening in which the governor springs 109 operate. This control handle is also provided with the brake 107 for stopping 100 the turn-table.

Revolvably attached to governor shaft 97 are governor members 108 secured by governor springs 109, which members are provided with rubbing elements 110 for engaging disc 104 in operation. As the speed increases, the members 110 rise against felt surface 104 thereby controlling the disc at a predetermined set speed.

Handle 105 is provided with a friction spring 111 which rubs on top plate 18, tending to maintain the handle and pointer in set position. The governor casing is provided with bottom cover 112 which is set in and burred, the other end of the governor casing being integral and provided with openings to permit the action of controller-handle and pointer 105 and the operation of the governor shaft 97. The governor casing is secured to top plate 18, which also is provided with openings to permit the operation of said handle 105 and shaft 97.

Referring to the governing apparatus 115 120 125 130 balls preferably of steel are inserted in governor members 108 and which contact

with felt surface 104' which is secured to disc 104. The governor casing 102 may be slit as shown by slots and bent inward to provide a spring or binding action of the thread on disc 104, thus holding speed control disc 104. This may be adjusted, if desired, to bring sufficient tension so that the spring 111 may be eliminated. This adjustment prevents back lash of control disc 104.

10 This is really a most important adjustment. 116 is a locating bearing bushing fastened into the governor housing 102 and constitutes the upper bearing of the governor shaft 97. The upper flange of bearing 116 fits removably into a hole in top plate 18 very accurately located on a radial line from the center of the turn-table to its flange 61 of the turn-table, thus determining the location of the air suction element or wheel 98 with reference to its co-acting member 61. The hole in the top plate is larger than the suction wheel 98 for assembly purposes. The governor casing is secured to top plate 18 by any suitable means, such as screws or the like.

25 I have discovered a relation which permits of swinging a reproducing system from a pivot at substantially the same distance from the center of the record as the diameter of the record and which still maintains the diaphragm or needle rocker in substantial tangency to every groove on the record.

Referring now to Fig. 2: AB represents a radius from the center through both concentric circles. CD represents a line at right angle to AB, commencing from the inner record groove. This line now is tangent to the inner circle since it is at right angles to the radius from the center. At the point of intersection of the radius with the outer circle at E, I also erect a right angle line FE of the same length. This now also is tangent. I find that if I now support an L-shape arm or supporting lever at C, whose outer leg is equal to CF and the other leg equal to FE, with the reproducer at E, a substantially tangent position of the rocker needle will be maintained to every circle. The rocker needle or diaphragm is tangent at the outer circle by definition. If now as the point E moves across the record toward D, it also goes forward so that it is contacting on a different radius in every circle until when it reaches G, if a line be drawn from A through it and a right angle taken from this line it will be found continually to nearly coincide with the tangent.

In actual construction it is not necessary to make the support arm in the form shown in this figure, but one may instead use that shown in Fig. 6, in which case the pivot is still C on the same parallelogram. The lever, instead of proceeding from C to F is substantially the diagonal of the parallelogram, but the support means for the needle is so arranged at the end that in the case of

an ordinary reproducer it is parallel with the line EF.

I have stated above that this arrangement does not produce absolute tangency. The variation at G is about 5 degrees. In progressing across the record then the point E goes slightly further forward making a true tangent. Lengthen the arm FE to a point slightly forward of the true radius AB as E'. This position then does not correspond with the absolute tangent line at the commencement of the record, but the variation from true tangency if the line FE be lengthened forward to a point E' of such a distance beyond E that when the arm FE' travels across the record to G', the axis of the reproducer will coincide with the tangent to the radius of the inner circle through that point G', then it will be found that the error of tangency of this axis or face of the reproducer with the tangency to the outer circle at point of contact is less than two degrees. In the specific case the lengthening of the line FE amounts to about $\frac{1}{8}$ ". In practice this latter method works the better. The outer circle is so much larger than the inner one that this slight lack of tangency has no appreciable effect. There are furthermore certain advantages in having the needle slightly forward of the radius which has a tendency to cause the needle to hug one side of the groove. This method also avoids making the side thrust too great.

Having thus described my invention, what I claim and desire to secure by Letters Patent is:

1. A reproducer for a phonograph comprising a stylus carrying member, a conical-shaped vibrating member rigidly secured to said stylus carrying member and entirely carried thereby, and supporting means for said stylus carrying member to permit a stylus rigidly secured thereto to follow a record to be played and transmit the vibrations of said stylus to said vibrating member, said stylus carrying member journaled in said supporting means operative over the record to be played, the axis of said journal being substantially at right angles to the axis of said conical shaped vibrating member.

2. A reproducer for a phonograph comprising a stylus carrying member, a conical shaped vibrating member rigidly secured to said stylus carrying member so that an element of said conical shaped vibrating member is substantially parallel to a disc to be played and entirely carried thereby, and supporting means for said stylus carrying member to permit a stylus rigidly secured thereto to follow a record to be played and transmit the vibrations of said stylus to said vibrating member, said stylus carrying member journaled in said supporting means operative over the record to be played.

3. In an organized phonograph a reproducer member in part consisting of a vibrating conical shaped member, a reproducer carrying arm pivoted to swing over a record to be played and carrying said conically shaped vibrating member, means provided whereby said vibrating member may oscillate around a carrying center on said carrying arm consisting of a journal thereon, and means for mounting said conical vibrating member with reference to said carrying arm so that said carrying arm and an adjacent surface of said vibrating member are substantially parallel.

4. In an organized phonograph a reproducer member in part consisting of a vibrating conical shaped member, a reproducer carrying arm pivoted to swing over a record to be played and carrying said conically shaped vibrating member, means provided whereby said vibrating member may oscillate around a carrying center on said carrying arm consisting of a journal thereon, and means for mounting said conical vibrating member with reference to said carrying arm so that said carrying arm and an adjacent surface of said vibrating member are substantially parallel, a stylus operating said conical vibrating member rigidly attached thereto and the axis of said stylus and the said conical vibrating member being substantially parallel.

5. A reproducer for a phonograph comprising a conical-shaped vibrating member rigidly secured to a stylus carrying member and entirely carried thereby, a stylus carrying member, and means for supporting said stylus carrying member to permit a stylus rigidly secured thereto to follow a record to be played and transmit the vibrations of said stylus to said vibrating member, said means consisting of a reproducer supporting arm, and means for supporting said stylus carrying member on said supporting arm consisting of a flexible mounting in combination with a handle attached to said stylus carrying member.

6. A reproducer for a phonograph comprising a conical shaped vibrating member rigidly secured to a stylus carrying member and entirely carried thereby a stylus carrying member and means of supporting said stylus carrying member to enable a stylus rigidly secured thereto to follow a record to be played and transmit the vibrations of said stylus to said vibrating member, said means for carrying said stylus carrying member consisting in part of reproducer head 48, a reproducer supporting arm 41, and a detachable securing means for securing the said reproducer head to said supporting arm.

7. A hornless phonograph comprising a reproducing unit provided with a stylus holder having a freely vibratory sound disseminating element entirely supported by and rigidly

attached to said stylus holder, a reproducer head having rigidly attached thereto said reproducer unit, and means for resiliently supporting in said reproducer head said stylus holder, said stylus holder and sound disseminating element being of relatively small mass while the reproducer head is of relatively large mass.

8. A hornless phonograph comprising a reproducing unit provided with a stylus holder having a freely vibratory sound disseminating element entirely supported by and rigidly attached to said stylus holder, a reproducer head having rigidly attached thereto said reproducing unit, and means for resiliently supporting in said reproducer head said stylus holder said stylus holder being carried by a stem formed integral therewith and projecting into a bore in said reproducer head.
